DESIGN FOR A TOBACCO POUCH

Jacques Schwalbe, New York, N. Y.

Application September 9, 1939, Serial No. 87,107

Term of patent 7 years

To all whom it may concern:

Be it known that I, Jacques Schwalbe, a subject of the King of Belgium, residing in the city, county, and State of New York, have invented a new, original, and ornamental Design for a Tobacco Pouch, of which the following is a specification, reference being had to the accompanying drawing, forming part thereof.

I claim:

The ornamental design for a tobacco pouch, as shown.

JACQUES SCHWALBE.
